(57) **CLAIM**

The ornamental design for a wheel, as shown and described.

DESCRIPTION

FIG. 1 is a front perspective view of the wheel design of the
present invention;

FIG. 2 is a front plan view thereof;

FIG. 3 is a rear plan view thereof; and,

FIG. 4 is a left side elevational view thereof, the right side
elevational view being a mirror image thereof.

The broken line showing of environment is for illustrative
purposes only and forms no part of the claimed design.
